J. F. O'CONNOR

HAND BRAKE

Filed Sept. 26, 1923

Fig. 1

UNITED STATES PATENT OFFICE.

JOHN F. O'CONNOR, OF CHICAGO, ILLINOIS, ASSIGNEE, BY MESNE ASSIGNMENTS, TO
W. H. MINER, INC., A CORPORATION OF DELAWARE.

HAND BRAKE.

Application filed September 26, 1923. Serial No. 664,889.

This invention relates to improvements in hand brakes.

One object of the invention is to provide a simple and efficient hand brake for railway cars, which is particularly adapted for use on flat and logging cars, and wherein the brake staff may be swung from vertical to horizontal position at the side of the car so as to clear the projecting portions of lumber, logs, or the like with which the car is loaded.

A more specific object of the invention is to provide a device of the character indicated, including a chain winding drum carrying a driven means, and a brake staff carrying a driving means adapted to engage the driven means, wherein the drum is mounted for rotation about a fixed axis, the staff is mounted for swinging movement from a vertical to a horizontal position, and the driving means is adapted to operatively engage the driven means in either of said positions with equal efficiency.

Other objects and advantages of the invention will more clearly appear from the description and claims hereinafter following.

In the drawing forming a part of this specification, Figure 1 is an end elevational view of a portion of a flat car, showing my improvements in connection therewith. Figure 2 is a vertical, sectional view corresponding substantially to the line 2—2 of Figure 1, the rotary parts being shown as moved through an arc of 90° from the position shown in Figure 1. Figure 3 is a vertical, sectional view corresponding substantially to the line 3—3 of Figure 2. And Figure 4 is a horizontal, sectional view corresponding substantially to the line 4—4 of Figure 3.

In said drawing, 10 indicates the usual floor of the flat car, 11 the end sill to which is attached the brakeman's platform 12, and 131 one of the stake receiving sockets which are fixed to the sides of the car.

The improved brake mechanism, as shown, comprises, broadly, a brake staff A; a hand wheel B; a combined driving gear and bearing member C; a brake drum D; a locking collar E; a pivoted support F; and a pair of brackets G and H.

The drum D is in the form of a two part hollow cylindrical sleeve, the sleeve being divided longitudinally, the sections 13 of the

sleeve being exact counter parts. The sleeve D is mounted for rotation about an axis disposed in a plane parallel to the end of the car and is arranged at an angle of 45° to the vertical. The lower end of the drum D is reduced, as indicated at 14, to provide a bearing portion journaled in the lower end of the bracket 15, projecting downwardly from the bottom of the car and fixed to the end sill 11 by rivets or any other suitable fastening devices. The bearing portion 14 is also divided longitudinally, each part of the same being formed integral with the corresponding section 13 of the drum. The upper end portion of the sleeve forming the drum D is journaled in a bearing member 16 formed on the outer end of an arm 17 laterally projecting from the bracket G secured to the end sill 11 by rivets or any other suitable means. At its upper end, the drum D is provided with a beveled ring gear 18, the gear 18 being composed of two sections each of which is formed integral with the corresponding section 13 of the drum. The upper end of the drum D is also provided with a socket 19, one-half of the socket being formed in each section 13. The socket 19 is preferably of spherical shape with the center thereof in alignment with the axis of the drum. At opposite sides, adjacent the ring gear, each section 13 is provided with ears 20 adapted to receive rivets by which the sections are held together. The sections are also held together by an eyebolt 21, which serves as a means for anchoring the end of the bracket chain to the drum D.

The brake staff A has the lower end thereof formed of square cross-section as indicated at 22. At the upper end the staff A is provided with the usual hand wheel B rigidly secured thereto, in any suitable manner, so as to rotate the same.

The combined driving gear and bearing member C is in the form of a casting having an angular socket 23 adapted to receive the square portion 22 of the staff A, to which it is rigidly secured as by a pin 24 extending transversely through the casting and the square portion of the staff. The upper end of the casting C has a cylindrical exterior and is journaled in a horizontally extending plate 25 integral with the supporting

bracket F, which is pivotally mounted on the bracket G, the latter being provided with a boss 26 adapted to receive the trunnion 27 extending laterally from the former and held in position by a cotter pin 28. Immediately below the cylindrical portion of the casting C, an annular rib 29 is provided adapted to engage and bear on the lower surface of the plate 25. The portion immediately below the rib 29 is of conical form and terminates in a hollow spherical member 30 adapted to work in the socket 19 of the drum D and form a bearing portion for the lower end of the brake staff. The spherical member 30 and the socket 19 of the drum D coact in the manner of a ball and socket joint, so that the staff may be swung upwardly and downwardly. The conical portion of the casting C is formed with a series of peripheral teeth 31 thereby presenting a bevel gear adapted to coact with the teeth of the beveled ring gear 18.

The staff A is also provided with a ratchet wheel 32 of well-known construction mounted on the square portion of the former for rotation therewith and is adapted to bear on the upper surface of the plate 25. A locking dog 33, adapted to coact with the ratchet wheel 32, is pivotally mounted on the plate 25 by the bolt 34.

To hold the staff in vertical position the following means is provided. The bracket G is formed with an upper, laterally extending, arm 35 terminating in a hook shaped portion 36 providing a socket having an upwardly extending curved flange 37 adapted to engage within an annular flange 38 downwardly extending from the collar E slidably mounted for vertical movement on the staff A. It will be evident that when the flange of the collar E is engaged over the flange 37 of the arm 35, the staff will be positively held in its vertical position. To disengage the staff from the socket of the bracket 35, the collar E is moved upwardly on the staff A thereby disengaging the same from the flange 37, whereupon the staff may be swung downwardly to the horizontal position shown in dotted lines in Figures 1 and 3.

To retain the staff A in the horizontal position, the bracket H is provided, the same being in the form of a U-shaped hook member rigidly secured to the end sill 11 by rivets. The short arm of the U-portion of the bracket H is provided with a spring clip 40 adapted to work in a slot in the arm of the bracket and spring into position over the staff when the same rests within the hook portion of the bracket.

To permit the brake staff A to be swung into position, the brakeman's platform 12 is pivotally mounted so as to swing upwardly, the same being supported by a pair of brackets 41 fixed to the end sill 11 by rivets and straps 42 secured to the lower side

of the platform and pivotally connected with the brackets 41.

In assembling the device, the spherical end 19 of the combined bearing and gear C is first engaged within the socket portion of one of the sections 13 of the brake drum D. The opposite section 13 is then secured in position by the rivets 120 and the eye-bolt 21 thereby retaining the spherical end permanently within the socket. The pivoted bracket F is next assembled with the combined gear and bearing member C by inserting the cylindrical bearing portion of the latter within the opening provided in the plate. The staff A, after having the ratchet and collar E placed thereon, is then assembled with the member C.

The operation of the device is as follows. When the brake staff is in the full line position shown in the drawing, that is, when the same is disposed in vertical position, rotation of the hand wheel will effect rotation of the chain winding drum in either direction through the inter-engaging gears C and 18, in a well-known manner. When it is desired to operate the brakes from the side of the car, the flange of the collar E is disengaged from the flange 37 of the bracket 35 and the staff A swung to the position shown in dotted lines in Figures 1 and 3, the brakeman's platform 12 being first swung upwardly out of the way. It will be evident that in swinging the staff A from the vertical to the horizontal position, the gear teeth 31 will first be disengaged from the upper side of the ring gear 18 and reengaged at the lower side thereof when the staff reaches the horizontal position. In the swinging movement of the staff, the pivoted bracket F together with the locking dog and ratchet wheel will be carried therewith, as clearly shown in Figure 1. It will be evident that rotation of the locking dog 33 around the axis of the staff is effectively prevented by the bracket F being pivotally mounted on the fixed bracket G at right angles to the axis of rotation of the staff. It will also be noted that, whereas the dog 33 is foot-controlled when the staff A is upright, said dog becomes gravity actuated to operative position, when the staff is in horizontal position. The brake staff may be operated from either position without in any way altering the effective leverage thereof.

When the brake staff is in lowered or horizontal position, it will be noted that there is no part of the brake mechanism which projects above the level of the floor so all possibility of interference with projecting material is absolutely eliminated. Furthermore, the hand wheel in the lowered position of the staff is at a convenient and accessible point for the brakeman, whether he be running along the ground or on the usual step.

I have herein shown and described what

I now consider the preferred manner of carrying out my invention, but the same is merely illustrative and I contemplate all changes and modification that come within the scope of the claims appended hereto.

I claim:

1. In a hand brake for railway cars and the like, the combination with a chain winding drum; of a brake staff adapted to be disposed in either a vertical or horizontal position; coacting driving means on said drum and staff adapted to be brought into operative driving relation when the staff is moved to either of said positions.
2. In a brake mechanism, the combination with a chain winding member; of a brake staff adapted to be disposed in either a vertical or horizontal position, said staff being swingingly mounted for movement from one of said positions to the other; coacting driving elements fixed to said winding member and staff, respectively, said driving elements being adapted to directly engage each other when the staff is disposed in either of said positions.
3. In a brake, the combination with a chain winding member having a gear thereon; of a swingable brake staff adapted to be disposed in either a vertical or horizontal position; means for holding said staff in either of said positions; a gear on said brake staff so disposed as to directly engage the gear on said member when the staff is disposed in either of said positions.
4. In a brake, the combination with a chain winding member; of a rotary brake staff pivotally mounted at its lower end, whereby, the staff may be swung to either a vertical or horizontal position; means for holding the staff in either of said positions; and coacting driving means on said staff and winding member, said driving means including an element fixed to the staff and an element fixed to said winding member, said elements being operatively disposed in direct engagement when said staff is in either of said positions.
5. In a brake mechanism, the combination with a rotatable, pivotally mounted brake staff; of a chain winding drum, said drum being disposed in an inclined position; and coacting driving means on said staff and drum, said means being operative when said staff is disposed in either a vertical or horizontal position.
6. In a brake, the combination with a rotatable brake drum having fixed driving means at one end thereof; of a rotatable brake staff having its lower end pivotally mounted to swing about a point coincident with the axis of rotation of said drum, whereby said staff may be moved to either a horizontal or a vertical position, said brake staff having fixed driving means adjacent

its lower end adapted to engage said first named driving means.

7. In a brake, the combination with a rotatable brake staff; of a brake drum, said staff having the lower end portion thereof swiveled to said drum by means of a ball and socket connection having the center of the ball portion thereof coincident with the axis of rotation of said drum, whereby, said staff may be disposed either in a vertical or a horizontal position; and means for operatively connecting said staff and drum in driving relation in either of said positions of said staff.

8. In a hand brake, the combination with a rotatable brake staff having a beveled gear at the lower end thereof, said gear being provided with an extension disposed axially of said staff and having a spherical portion at the lower end thereof; a rotary brake drum having an axially disposed socket at the upper end thereof adapted to movably accommodate said spherical portion whereby said staff may be swung to either a vertical or horizontal position, said drum being divided longitudinally and having a beveled gear at the upper end thereof adapted to mesh with said first named gear; and means for holding said staff in either of said positions.

9. In a hand brake, the combination with a rotatable brake staff; of a rotary chain winding drum; a ball and socket connection between said staff and drum whereby, said staff may be disposed either in a horizontal or vertical position; coacting driving means on said staff and drum; means for holding said staff in vertical position including a bracket having a portion partly surrounding said staff and a sleeve slidable on said staff adapted to embrace said portion of said bracket.

10. In a hand brake of the flat car type, the combination with a rotatable operating staff adapted to assume an operating position either above or below the floor level of the car; of a bracket in which said staff is journaled; said bracket being pivotally mounted on the car structure and confined to pivotal movement about an axis extending lengthwise of the car; brake tensioning means rotatably supported on the car structure; co-operable driving devices on said means and staff co-operable in both of said operative positions of the staff; and means co-operable with said staff for preventing rotation thereof in an unwinding direction when the staff is in either of its said operative positions.

In witness that I claim the foregoing I have hereunto subscribed my name this 21st day of September, 1923.

JOHN F. O'CONNOR.
